UNITED STATES PATENT OFFICE.

NEWELL SILL JENKINS, OF DRESDEN, GERMANY.

PORTABLE MELTING APPARATUS.

SPECIFICATION forming part of Letters Patent No. 653,007, dated July 3, 1900.

Application filed February 7, 1900. Serial No. 4,383. (No model.)

To all whom it may concern.

Be it known that I, NEWELL SILL JENKINS, a citizen of the United States of America, and a resident of Dresden, in the Kingdom of Saxony, German Empire, have invented certain new and useful Improvements in Portable Melting Apparatus, of which the following is a specification.

This invention refers to improvements in portable melting apparatus, and has for its object to provide such apparatus with a device for regulating and controlling the admission of gas in order to regulate the heat on the fusing materials especially used for dentists' purposes.

In my United States Patent No. 585,442, dated June 29, 1897, I have shown an apparatus to which the improvements of the present invention shall be applied. Said apparatus consists mainly, as described and illustrated in my former United States Patent mentioned above, of a muffle lined inside with asbestos, open at front, and provided at its bottom with a hole, said muffle resting on a fork-shaped carrier capable of being shifted on a vertical rod or a support into the proper height for working purposes. To that apparatus belongs a melting-ladle provided with a small protecting-cover, which ladle is to be inserted into said muffle. To that apparatus, furthermore, belongs a gas jet or burner placed underneath the muffle, the flame of which is directed against the ladle and may be increased by bellows or air-pressure apparatus.

Now this present invention refers to a device in combination with the said apparatus for regulating and controlling the supply of gas for the said flame. In the annexed drawings I have shown as much of my patented apparatus as is necessary to explain the present improvements.

Figure 1 shows a side view, and Fig. 2 a ground plan, of the apparatus.

45 *a* is the muffle, open at front, and *c* is the hole in the bottom of the muffle.

b is the carrier on which the muffle is held and adjusted in proper working height on rod *e*.

g is a carrier fixed to the muffle for supporting the arm of the ladle. (Not shown in the drawings.)

On the base-plate *h*, upon which the vertical rod *e* is fixed, are mounted two pipes, *m* for the gas, and *n* for the air. The two pipes are provided at their exterior ends with egg-shaped parts *m'* and *n'* for the gas and air hose to be affixed, which lead gas and air under pressure into the two pipes, respectively. The two pipes run together at the end, where they are bent in an upward direction underneath the muffle *a*, the gas-pipe forming at the united part the outer shell and the air-pipe forming the inner core, and these combined pipes are provided at their uppermost ends with suitable holes with which they terminate in a cap *o*, which is the burner proper.

The gas-pipe *m* is provided with a cock or valve *p*, the handle of which, *q*, is prolonged, so as to overlie a segmental-shaped scale *r*.

If now the operator has adjusted the muffle *a* to proper height for working and the stream of gas and air issuing from the burner-cap *o* being ignited, he may regulate this flame and its intensity upon the fusing material at will by adjusting the admission of gas according to scale by the handle *q*. The cock or valve *p* may be fully opened in the beginning of the operation; but as soon as the material may become fused it is very material that the heat may be modified, so as not to overdo the melting process and to spoil the result of the operation. The operator is guided in his regulating action by the scale *r*.

I claim as my invention—

1. The muffle *a*, of refractory material having a hole in the bottom and an opening in the front, the carrier *b* connected to the muffle and having a hole therein, a vertical supporting-rod *e* passing through the hole in the carrier, and a screw for clamping the carrier and muffle to said rod, in combination with the arm *g* pivoted at one side to the muffle so that its free end can be swung around opposite the opening in the front of the muffle, substantially as set forth.

2. The muffle *a* of refractory material hav-

ing a hole in the bottom and an opening in the front, the arm *g* pivoted to said muffle, and the rod *e* for supporting said muffle, in combination with the pipes *m* and *n* for gas 5 and air a burner at the end of said pipes below the opening in the bottom of the muffle, a cock *p*, in the gas-pipe *m*, a graduated scale *r* adjacent to said cock and an arm *q* secured to said cock and extending over said

scale, substantially as and for the purposes to set forth.

In testimony that I claim the foregoing as my invention I have signed my name in presence of two witnesses.

NEWELL SILL JENKINS.
